UNITED STATES PATENT OFFICE.

FRANCIS JARVIS PATTEN, OF NEW YORK, N. Y., ASSIGNOR TO J. M. SEYMOUR,
OF BRICK CHURCH, NEW JERSEY.

SYNCHRONOUS MULTIPLEX TELEGRAPHY.

SPECIFICATION forming part of Letters Patent No. 428,225, dated May 20, 1890.

Application filed January 10, 1890. Serial No. 336,581. (No model.)

To all whom it may concern:

Be it known that I, FRANCIS JARVIS PATTEN, a citizen of the United States, residing at New York, in the county of New York and State of New York, have invented certain new and useful Improvements in Sending and Receiving Instruments for Multiplex Telegraphs, of which the following is a specification.

My invention consists in the organization of receiving apparatus designed to produce ordinary Morse signals in a system of synchronous multiplex telegraphy. In such systems the relays are actuated by a series of intermittent impulses; and the object in devising special forms of receiving-instruments is to produce an organization of devices which will respond clearly to such intermittent currents. Ordinary receiving-instruments will chatter or vibrate and the sounder will not produce the signal sent by the key.

In the drawings, Figures 1 and 2 are a plan and end elevation of the receiving-relay. Fig. 3 shows one set of instruments arranged for sending and receiving by ordinary Morse writing in the multiplex system between two stations X and Y, connected by a main-line circuit, one set of instruments being shown in operation at each station, those at Y sending and those at X receiving.

Referring to Figs. 1 and 2, on a base B is mounted an ordinary relay-magnet M, which instead of the ordinary form of armature has placed in front of its poles a thin iron ribbon, so arranged that it can be stretched rigidly. It is fixed in one end in a post p' , and, passing through the slot in the post p' , is fastened to a set-screw S^3 , by means of which the ribbon can be given the proper degree of tension. The magnet M is adjusted in the ordinary way by means of the set-screw S^2 , so that the magnet-poles may be approached to or moved away from the ribbon. When intermittent impulses of current are sent into the coils of the magnet M and connected in the main-line circuit, the ribbon a is maintained in constant vibration; but when at rest the contact-point k rests against the adjustable point S' . Two such instruments are used in conjunction with each other, as shown in Fig. 3, to cause an ordinary Morse sounder to respond to the signals of the key. The

manner in which this is accomplished will be understood from an examination of Fig. 3, in which a single set of sending and receiving instruments is shown at the stations X and Y, Y being represented as sending to X. A description of the operation of these instruments at one station will answer for both.

Rv is the receiving-relay, just located in the main-line circuit. Close to it, and preferably mounted on the same base, is an auxiliary relay Ar of similar construction, and a narrower and heavier instrument to operate on a local circuit and battery. When the key K at Y is depressed, as shown, the receiving-relay Rv receives a series of intermittent impulses of current. The ribbon a^2 is maintained in constant vibration, so that the local circuit of the auxiliary relay is opened. This allows the ribbon of the auxiliary relay to fly back against the contact-stop and close the circuit of the sounder D^2 . If, however, the key K is open, the impulses in the receiving-relay Rv cease, the ribbon a^2 strikes its back contact, and the circuit of the auxiliary relay Ar is closed, the ribbon a^4 is drawn away from its contact, and the sounder-circuit is open. In this way the sounder is caused to follow the motions of the key, and as the same operations are repeated at the distant station signals can be transmitted with a key and sounder, in ordinary Morse writing, with intermittent-current impulses.

While there may be nothing essentially novel in the instruments shown in Figs. 1 and 2, I desire to claim in this application especially the combination of such instruments in the manner shown in Fig. 3, by which a sounder can be made to follow the key and produce ordinary Morse writing in a system of synchronous multiplex telegraphy.

Having thus described my invention, what I claim, and desire to secure by Letters Patent of the United States, is—

1. A main line including an electrical generator, which continuously sets up currents of alternate polarity over the line, and a relay having a reed or ribbon armature kept continuously vibrating, in combination with an auxiliary relay included in a local circuit with the reed or ribbon armature and a local sounder included in a second local circuit

with the armature of the auxiliary relay, substantially as described.

2. In a synchronous multiplex telegraph, a pair of distributers connected by a main line 5 including an electrical generator adapted to set up constantly over the line alternating currents, a series of transmitters connected to the distributer-circuits, and a series of receiving-relays, one for each transmitter, said 10 relays having reed armatures and local-circuit connections, substantially as described.

3. In a synchronous multiplex telegraph, a pair of distributers connected by a single main line, which includes in its circuit a main-line electrical generator adapted to set up 15 continuously rapidly-recurring alternating electrical currents, multiplex transmitters, and receivers connected to the distributers,

the receivers having reed armatures, substantially as described.

4. In a synchronous multiplex telegraph, a main line connected to a pair of distributers, including in its circuit a main-line battery having a continuously-acting pole-changer, which rapidly reverses the direction of the 25 battery-current over the line, in combination with a series of transmitters for each distributor and similar series of receiving-relays, said relays having reed armatures fixed at their opposite ends, and secondary relays 30 with local sounders and circuit connections, substantially as described.

FRANCIS JARVIS PATTEN.
